UNITED STATES PATENT OFFICE.

LOTHAR R. ZIFFERER, OF NEW YORK, N. Y.

DESIGN FOR AN EXPANSIBLE SHIELD.

46,765.

Specification for Design.

Patented Dec. 8, 1914.

Application filed December 4, 1913. Serial No. 804,774. Term of patent 3½ years.

To all whom it may concern:

Be it known that I, LOTHAR R. ZIFFERER, a citizen of the United States, residing at New York, in the county and State of New York, have invented a new, original, and ornamental Design for Expansible Shields, of which the following is a specification, reference being had to the accompanying drawing, forming part thereof.

The figure is a view in elevation of the expandible shield.

I claim:

The ornamental design for an expandible shield, substantially as shown.

LOTHAR R. ZIFFERER.

Witnesses:

EPHRAIM BANNING,
Wm. P. BOND.
